CATALYTIC CRACKING OF HEAVY HYDRO-CARBONS IN TWO STAGES

Gwilym Islwyn Jenkins, Sunbury-on-Thames, England, assignor to Anglo-Iranian Oil Company Limited, London, England, a British joint-stock corporation

Application July 29, 1948, Serial No. 41,268
In Great Britain August 9, 1947

6 Claims. (Cl. 196—49)

1

The invention relates to the catalytic cracking of heavy hydrocarbons, such as wax distillates.

The reaction products obtained by the catalytic cracking of heavy hydrocarbons, such as wax distillate, may conveniently be divided into three fractions, viz. gaseous hydrocarbons, cracked motor gasoline and cracked gas oil, all three fractions boiling below the boiling range of the feedstock. We have found that the conditions under which the cracking reaction is carried out may be varied to obtain on the one hand a cracked motor gasoline having a high octane number, and of commercial value, without re-treating or blending, in which case the cracked gas oil is of poor quality and is of doubtful value, particularly as a Diesel fuel, or on the other hand a gas oil of much better quality, and a lower yield of motor gasoline of lower octane number. Thus, for example, if a high severity cracking process resulting in approximately 75 to 80% feedstock destruction is employed, there is a yield of 33% gasoline of 81 octane number and a yield of 18% gas oil having a Diesel index of only 7. Such a gas oil can only be utilised as a blending stock for the improvement of the pour-point of a fuel oil. If a low severity cracking process be employed, for example, a process carried out under conditions of high feed rate and relatively low catalyst circulation rate such that the feedstock destruction amounts to 40 to 45%, there is a 15% yield of gas oil having a Diesel index of 20, and a 17% yield of motor gasoline of 77 octane number. Thus although the Diesel index of the cracked gas oil has been increased from 7 to 20, the yield has only fallen by 3% and furthermore such small decrease is more than compensated for by the increased feed-rate permissible at the lower feed-stock destruction. The low severity cracking process suffers from the disadvantage, however, that there is a large residue amounting to 55% to 60% of the feedstock and having substantially the same boiling range as the feedstock.

The invention has among its objects to provide a process which embodies the advantages of both the high severity and low severity cracking processes so as to obtain the maximum yields of gasoline, gas oil and fuel oil having the optimum octane number, Diesel index and pour-point respectively.

According to the invention there is provided a two-stage process for the catalytic cracking of a heavy hydrocarbon feedstock, such as wax distillate, in which in the first stage the feedstock

5

is cracked under conditions resulting in relatively low feedstock destruction to give a high yield of gas oil suitable for use as a Diesel fuel, while in the second stage the residue from the first stage is cracked under conditions resulting in relatively high feedstock destruction to give a high yield of good quality motor gasoline and a residue constituting a source of fuel oil having a low pour-point due to the presence in the residue due to cracked gas oil.

10 The process of the invention may be carried into effect in various ways according to refinery requirements and in the use of any desired type of catalytic cracking reactor.

15 Thus, one convenient method of operation, which is described with reference to the accompanying diagram, comprises passing the feedstock through line 10 to a reactor 11 wherein it is cracked under low severity conditions. The 20 reaction products and unchanged feedstock are passed via line 12 to a fractionator 13 where the gasoline and lighter hydrocarbons are separated as overhead through line 14, and a gas oil having a high Diesel index as side stream through line 15. A residue boiling above the gas oil range 25 is separated as bottoms through line 16. The overhead product is passed to a second fractionator 17 where the gas is separated overhead through line 18 and the stabilised gasoline as 30 a bottoms product through line 19, the residue from fractionator 13 being passed to a second reactor 20 where it is cracked under high severity conditions resulting in the production of a gasoline of high octane number. The 35 reaction products from the second reactor are passed through line 21 to a third fractionator 22 where the gasoline and lighter hydrocarbons are separated as overhead through line 23 and a bottoms product withdrawn through line 24 consisting of residual material containing cracked 40 gas oil produced in the second reactor.

45 The overhead products from the third fractionator 22 may be passed through line 25 to the second fractionator 17 in conjunction with the overhead products from the first fractionator, so that the gasoline produced in the first reactor is improved in octane number by the addition of the gasoline of higher octane number produced in the second reactor. If desired, however, the 50 overhead product from the third fractionator 22 may be passed through line 26 to a separate stabiliser 27 so as to provide a gasoline of high octane number as compared with the gasoline of low octane number separated from the second fractionator, the gasoline being removed as a bot-

2

toms product through line 28 and the gas overhead through line 29.

The two-stage process of the invention may be carried into effect according to any of the well-known operating principles. Thus, for example, both low-conversion and high-conversion operations may be carried out in reactors, both of which are operated on the normal downflow or bottom catalyst draw-off, fluidised bed principle. Alternatively, it is particularly satisfactory to use a first reactor operating on the well-known upflow fluidised principle, in order to deal conveniently with the high linear velocities often necessary for low conversion, while the second reactor is operated on the normal downflow principle. Where both reactors are of the fluidised or moving bed type, it is possible to utilise either a single regenerator serving both reactors, or a separate regenerator for each reactor.

The improvement obtained by means of the process according to the invention is clearly brought out in the following tables.

Table I gives the experimental results obtained when processing a wax distillate of Iranian origin on a synthetic silica-alumina catalyst under conditions of high and of low cracking severity. The reactor temperature, pressure and dilution were identical in both cases, but the oil throughput, expressed as weight of oil per hour per unit of weight of catalyst in the reactor $W_o/H/W_c$, was more than twelve times as great in the low severity operation as in the high severity operation. In order to provide direct assessments of the two modes of operation the experimental data provided in Table I have been transferred to comparative bases and the results are given in Tables II and III. In Table II the high and low severity operations are compared on the basis of equal oil feed rate, a value of 10,000 barrels per stream day being chosen as the basis for comparison. In Table III the two operations are compared on the basis of equal quantities of catalyst i. e. approximately equal reactor dimensions. Table IV gives the results of operating the two-stage process according to the invention, while Table V gives a comparison between the two-stage process and the normal single stage process.

In the following tables and throughout this specification the feedstock conversion is defined as 100 minus the volume percentage of material, in the reaction product, boiling above a true boiling point temperature of 430°F .

Table I

Feedstock—wax distillate of Iranian origin.
Catalyst—synthetic silica-alumina.

	High Severity	Low Severity
Reactor Conditions:

¹ Basic fresh feed.

It will be seen from a consideration of Table II that although the reaction space required for processing 10,000 B. P. S. D. at a conversion of 24.5% is less than one-tenth of that required for the same quantity of feed at 60% conversion, the gas oil yield is only 280 B. P. S. D. less at the lower conversion while the Diesel index is 13 units higher. It will be seen from a consideration of Table III that the low conversion operation yields 1450 B. P. S. D. of gas oil of 20 Diesel index as compared with only 136 B. P. S. D. of 7 Diesel index in the high conversion operation.

It is also clear from Tables IV and V that the two-stage process is advantageous as compared with the single stage process in many respects and particularly with regard to gas oil yield and quality. Thus, the total catalyst requirement in the two-stage process is 52,000 lbs. less than in the single stage process. The single stage process gives more gas and volatiles, thus requiring a larger gas-handling plant, and some 900 B. P. S. D. more cracked residue. The total quantity of gas oil in the two-stage process, is 2,500 B. P. S. D. of which 1450 B. P. S. D. is at 20 Diesel index and the remainder is at 7 Diesel index. The Diesel index of the combined material is estimated as being 15. With the single stage process, the gas oil yield is only 1730 B. P. S. D. and the Diesel index is 7. The single stage process gives 4090 B. P. S. D. of gasoline of 81 octane number, while by combining the two gasolines from the two-stage process there is a total yield of 4530 B. P. S. D. at an estimated octane number of 79, or, on an alternative basis, the two-stage process yields 358,000 "barrel-octane numbers" as compared with 331,000 "BON" from the single stage process.

I claim:

1. A two-stage process for the catalytic cracking of a hydrocarbon feedstock boiling above the gas oil range, comprising passing the feedstock to a reactor wherein it is cracked at a relatively high space velocity resulting in approximately 40-45% feedstock destruction, passing the reaction products from the reactor to a fractionator

6

where gasoline having an octane number about 77 and lower hydrocarbons are separated as overhead, a gas oil having a Diesel index of approximately 20 as a side stream and a residue boiling above the gas oil range as bottoms, removing the gas oil from the system, passing the overhead product to a second fractionator where the gas is separated overhead and the stabilized gasoline as a bottoms product, passing the residue boiling above the gas oil range to a second reactor

10 where gasoline having an octane number about 81 and lighter hydrocarbons are separated as overhead, and a bottoms product is withdrawn consisting of residual material containing cracked gas oil having a Diesel index about 7 produced in the second reactor and constituting a source of fuel oil.

15 2. A two-stage process according to claim 1, in which the overhead products from the third fractionator are passed to the second fractionator in conjunction with the overhead products from the first fractionator and gasoline is separated from the second fractionator, the yield of gasoline so produced having a greater total barrel octane number than the yield of gasoline which could be obtained by cracking the original feedstock in a single stage.

25 3. A process according to claim 1, in which the overhead product from the third fractionator is passed to a separate stabilizer where the gas is separated overhead and the gasoline of octane number approximately 81 is separated as a bottoms product.

30 4. A process according to claim 1, wherein the first reactor operates on the up-flow fluidized principle, while the second reactor is operated on the down-flow principle.

35 5. A process according to claim 1, wherein cracking in the first reactor is carried out at a temperature of 900° F., a pressure at the outlet of the reactor of 10 lbs./sq. in., and a space velocity of 10.3 Wo/H/Wc.

40 6. A process according to claim 1, wherein the cracking in the second reactor is carried out at a temperature of 900° F., a pressure at the outlet of the reactor of 10 lbs./sq. in., and a space velocity of 0.81 Wo/H/Wc.
